SHOE AND METHOD OF MAKING

Stanislav V'Soske, Grand Rapids, Mich.

Application May 17, 1943, Serial No. 487,205

4 Claims. (Cl. 36—9)

This invention relates to improvements in shoes and method of making.

The main objects of this invention are:

First, to provide a shoe which is at least formed of materials other than rubber or leather which may be very economically produced and at the same time is strong and durable and attractive in appearance.

Second, to provide a shoe embodying these advantages which may be readily formed by operators accustomed to use existing machinery with a minimum of training and effort.

Third, to provide an integral shoe element or element for use in the manufacture of shoes comprising a sole portion and an upper or vamp portion as an integral structure.

Objects relating to details and economies of the invention will appear from the description to follow. The invention is defined and pointed out in the claims.

A preferred embodiment of the invention is illustrated in the accompanying drawings, in which:

Fig. 1 is a perspective view of a shoe embodying the features of my invention.

Fig. 2 is an enlarged view in fragmentary vertical section on line 2—2 of Fig. 1.

Fig. 3 is an enlarged fragmentary view partially in vertical section at the toe of the shoe.

Fig. 4 is an enlarged fragmentary section on line 4—4 of Fig. 1.

Fig. 5 is an inverted view of the shoe element or unit showing the shoe element prior to folding the edge portions of the fabric blank upwardly to form the upper.

Fig. 6 is a plan view of the top portion of the vamp or upper which, in the embodiment illustrated, is formed as a separate piece.

Fig. 7 is an enlarged fragmentary sectional view of the shoe element showing the relation of a beading strip arranged to provide the appearance of a welt.

Fig. 8 is an enlarged fragmentary view of the woven fabric constituting the foundation and main body portion of the shoe element.

In the embodiment illustrated, 1 represents the sole, 2 the upper or main or body portion of the vamp, and 3 a complementary top vamp portion, and 4 the heel.

The characteristic feature of my invention is 50 the forming of a shoe element designated generally by the numeral 5, in Fig. 5, which is formed of a piece of fabric shown at 6, Fig. 8, this fabric being a woven fabric made up of multi-thread cords of substantial diameter—that is, the object

being to provide a strong fabric. This unit comprises a sole foundation portion 7, a shank portion 8, and a heel portion 9 which portions are surrounded by the border portion 10. This border portion is patterned so that it may be shaped or conformed into the upper 2.

In the preferred embodiment, nap strands 11 are looped into the sole, shank and heel foundation portion to provide tufts 12 of substantial depth. These tufts are closely set—that is, they are set so as to be in mutually laterally supporting relation to each other as is illustrated in the drawings.

I preferably stitch a beading strip 13 around the sole foundation portion to provide a welt-like appearance at the point where the upper portion joins the sole portion. This is particularly desirable when the upper portion is turned upwardly at an angle to the sole portion in forming the shoe. This is clearly shown in the drawings.

In the manufacture of the shoe, a layer of plastic material 14 is applied to the upper surface of the foundation portion and this serves the double purpose of providing a suitable supporting surface for the insole 15 and it also serves to bind the tufts. Latex is suitable for the purpose but there are other plastic and adhesive materials which will serve satisfactorily.

I also preferably coat at least the ends of the tufts with a plastic material 16 or suitable water resisting or repellent characteristics and this also serves to stiffen and bind the tufts and provide an effective tread surface. It prevents the tufts from spreading out in use.

A sock lining 17 may be arranged on the insole 15.

The lining 18 is preferably adhesively secured to the upper fabric as is indicated in the drawings at 19, see Fig. 2.

The border portion 10 is notched at 20 and at 21 so that when the upper portion is conformed the edges of these notches may be brought together and stitched in vertical seams. The upper portion 3 is stitched by overcast stitching to the upper edge of the border element 10 providing a suitable beading appearance indicated at 22, this of course being a matter of design as the upper portion might be shaped or patterned to form

the complete upper or vamp. A binding 23 of overcast stitching is provided around the sides and heel portion of the upper.

A suitable counter is shown at 24.

By thus forming and arranging the parts, I 55 provide a very satisfactory structure which may

be formed entirely of materials other than leather. The shoe is strong, keeping its shape, and it is attractive in appearance and is not clumsy. By forming the sole and the main portion or upper in one piece, manufacture is not only facilitated but the finished shoe is very strong and there is no possibility of the sole loosening from the upper.

I have illustrated and described my improvements in an embodiment which I consider very practical. I have not attempted to illustrate various modifications and adaptations for shoes of different designs as it is believed that this disclosure will enable those skilled in the art to embody and adapt my invention as may be desired.

Having thus described my invention, what I claim as new and desire to secure by Letters Patent is:

1. A shoe comprising a foundation fabric having integral sole, shank and heel portions surrounded by an integral upper portion of substantial width extending beyond the edges of said sole, shank and heel portions to constitute sides of the shoe upper, tuft material looped into the sole and shank portions of said foundation in predetermined sole and shank patterns to provide an outer sole tread wear surface for the sole portion and an outer shank portion, the heel portion of said foundation and said upper portion being without tufting, a cord of fibrous material disposed below the foundation fabric at the edges of the tufts in side supporting relation to the outer tufts and stitched to the foundation, the tufts intermediate the outer tufts being closely arranged in side by side supporting relation to each other, and a platform arranged upon said sole, shank and heel portions with its edges in supporting engagement with said upper portion adjacent the juncture thereof with said sole, shank and heel foundation portions.

2. A shoe comprising a foundation fabric having integral sole, shank and heel portions surrounded by an integral upper portion of substantial width extending beyond the edges of said sole, shank and heel portions to constitute sides of the shoe upper, tuft material looped into the sole and shank portions of said foundation in pre-

determined sole and shank patterns to provide an outer sole tread wear surface for the sole portion and an outer shank portion, the heel portion of said foundation and said upper portion being without tufting, the tufts being closely arranged in side by side supporting relation to each other, and a platform arranged upon said sole, shank and heel portions with its edges in supporting engagement with said upper portion adjacent the juncture thereof with said sole, shank and heel foundation portions.

3. A shoe comprising a foundation fabric having integral sole, shank and heel portions surrounded by an integral upper portion of substantial width extending beyond the edges of said sole, shank and heel portions to constitute sides of the shoe upper, tuft material looped into the sole portion of said foundation in predetermined sole pattern to provide an outer sole tread wear surface for the sole portion, a cord of fibrous material disposed below the foundation fabric at the edges of the tufts in side supporting relation to the outer tufts and stitched to the foundation, the tufts intermediate the outer tufts being closely arranged in side by side supporting relation to each other, and a platform arranged upon said sole, shank and heel portions with its edges in supporting engagement with said upper portion adjacent the juncture thereof with said sole, shank and heel portions.

4. A shoe comprising a foundation fabric having integral sole, shank and heel portions surrounded by an integral upper portion of substantial width extending beyond the edges of said sole, shank and heel portions to constitute sides of the shoe upper, tuft material looped into the sole portion of said foundation in predetermined sole pattern to provide an outer sole tread wear surface for the sole portion, the tufts being closely arranged in side by side supporting relation to each other, and a platform arranged upon said sole, shank and heel portions with its edges in supporting engagement with said upper portion adjacent the juncture thereof with said sole, shank and heel foundation portions.
